AMMUNITION

Warren S. Reynolds, Stratford, Conn., assignor to
Remington Arms Company, Inc., a corporation
of Delaware

Application December 5, 1940, Serial No. 368,639

6 Claims. (Cl. 86—31)

The present invention relates to an automatic powder charger for cartridge shells, and has for an object to provide an automatic machine by means of which accurately measured charges of powder may be removed from a supply source, as for instance a gravity feed hopper, and successively fed into relation to and ejected into individual cartridge shells. To this end it is particularly proposed to provide a rotating conveyer drum having a series of powder charge receiving pockets arranged to move from the supply hopper to the ejection point in relation to the shell to be charged.

A further object is to provide such machine in which the individual charges of powder will be of uniform consistency, free from voids, as well as of uniform size and weight. To this end it is proposed to provide automatic compacting means which will compact the charge of powder in the drum pockets while in direct relation with the supplying hopper so that prior to the removal of the charge from the supply hopper there is positive assurance that the required amount of charge is in the pockets without voids, bridging or loose areas. It is further proposed to provide automatic detector means for testing or gauging the correct predetermined amount of the charge in the pockets of the conveyer drum during the transition from the hopper to the ejection point, and to provide automatic stop means for stopping the operation of the machine when there is a deficiency or absence of powder in the pockets. It is further proposed to provide ejection means which will positively insure the complete ejection of the powder charge to the cartridge shells.

With the above and other objects in view, an embodiment of the invention is shown in the accompanying drawings, and this embodiment will be hereinafter more fully described with reference thereto, and the invention will be finally pointed out in the claims.

In the drawings:

Fig. 1 is a plan view of a powder charger, according to the exemplary illustrated embodiment 45 of the invention.

Fig. 2 is a front elevation.

Fig. 3 is a vertical transverse sectional view, taken along the line 3—3 of Fig. 1.

Fig. 4 is a side elevation of the forward portion of the machine from the left hand side as seen in Fig. 2.

Fig. 5 is a side elevation of the forward portion of the machine from the right hand side as seen in Fig. 2.

Fig. 6 is a vertical longitudinal sectional view taken along the line 6—6 of Fig. 2.

Similar reference characters indicate corresponding parts throughout the several figures of the drawings.

Referring to the drawings the automatic powder charger for cartridge shells, according to the exemplary illustrated embodiment of the invention, comprises a rectangular base plate 10, near the forward edge of which there is mounted a yoke-shaped bearing bracket member 11 having outwardly extending foot portions 12—12 secured to the base by bolts 13, this bracket member being provided upon its upper side with a block 14 having a horizontal bore 15 therein in which there is rigidly secured, preferably by a force fit, the shank portion 16 of a forwardly projecting shaft 17 having a reduced diameter stud portion 18 at its forward end. This shaft 20 17 provides a fixed bearing for the rotatable powder charge transporting drum, as will presently more fully appear.

The bearing bracket 11 is arranged parallel to the forward edge of the base plate 10 adjacent its left hand edge, and adjacent the right hand edge of the base plate there are provided a right angular bearing bracket 19 secured by bolts 20 and a right angular bearing bracket 21 secured by bolts 22, these bearing brackets projecting partially over the right hand edge of the base plate and having their upright portions in spaced parallel relation to each other and to the forward edge of the base plate. A cylindrical bearing collar 23 is secured by welding to the bearing bracket 19 near its outer edge, and in alignment therewith a similar bearing collar 24 is secured by welding to the bracket member 21, and within these bearing collars 23 and 24 there is journaled a cam shaft 25, upon which the several cams which operate the automatic mechanism of the machine are mounted, as will presently more fully appear.

This cam shaft has secured upon its rearward end a gear 26 meshing with a pinion 27 secured upon a counter drive shaft 28 having bearing in a bearing collar 29 secured by welding to the bracket 19 near its inner edge and in a bearing collar 30 secured by welding to a right angular bracket 31, secured upon the base plate 10 by bolts 32, this bracket 31 being disposed in parallel spaced relation to the bracket 19. There is also secured upon the counter drive shaft 28 a pulley 33 engaged by a drive belt 34 extending from the pulley 35 of the driving motor 36, the base 37 of this motor being secured by bolts 38

to the base plate 10. The motor 36 is provided within a case 39 with multiple parallel reduction gearing, whereby the speed of the pulley 35 is reduced with respect to the actual motor speed.

A right angular vertically disposed bracket 40 is secured upon the forward side of the bracket 21 by means of bolts 41 and supports the several levers operated by the cams carried by the shaft 25, and as will presently more fully appear.

Upon the bearing shaft 17 there is mounted for intermittent rotary movement the cylindrical powder charge transporting drum member, indicated generally as 42, and which consists of a hub portion 43, a web portion 44 and a cylindrical rim portion consisting of a part 45 extending forwardly from the web portion and a part 46 extending rearwardly therefrom, the part 46 being substantially thicker and narrower than the part 45. A series of radially disposed equally spaced bearing formations 47 are provided upon the inner side of the rim part 45 having radial cylindrical passages 48 therein which extend to the peripheral surface of the rim and which constitute powder charge receiving pockets and bearing passages for plunger members, presently to be more fully described.

The rim part 46 is provided with a series of radial holes 49 in alignment with the passages 48 and substantially larger in diameter and which constitute pockets for receiving a locking pin for holding the drum 42 in fixed position between its intermittent rotary movements, as will presently more fully appear. Upon the outer periphery of the rim portion 46 there is provided a series of spaced ratchet notches 50 spaced in correspondence with the spacing of the holes 49, and which are adapted to be engaged by the ratchet feed mechanism, presently to be more fully described.

Upon the forward stud portion 18 of the shaft 17 there is engaged a plunger actuating cam member 51, the hub 52 of which is secured to the stud by a pin 53 and constitutes a collar for retaining the conveyer drum 42 against longitudinal shifting movement upon the shaft 17.

Within each of the passages 48 there is slidably engaged a plunger member 54, the outer end of which constitutes a base for the powder receiving pocket, while its inner end, which is provided with a head 55, is engaged with the periphery of the cam 51, a helical spring 56 being provided upon the plunger between the head and the bearing formation 47 to press the head 55 into engagement with the cam, and which exerts a retracting force upon the plunger with respect to the powder receiving pocket.

The high portion of the cam 51 maintains the plunger in the normal powder charge supporting position, while the low portion causes it to retract slightly as it enters the hopper and at its first position within the hopper, so as to allow an excess of powder to flow into the pocket, the slight projecting cam actuated movement of the plunger which follows causing the charge to be compacted within the pocket, thus eliminating voids and loose areas. The cam is provided in its lower portion with a radial slot 57, in which there is operatively engaged the mechanism for imparting ejecting movement to the plunger in the ejecting position of the drum, as will herein-after more fully appear.

At the right hand side of the conveyer drum there is mounted a vertically disposed supporting standard 58 of T-shape in cross-section, secured at its base 59 to the base plate 10 by means of

bolts 60, and having mounted upon its upper flat rectangular top portion 61 the powder containing hopper 62, the rectangular base portion 63 of which is secured by bolts 64 to the top portion 61. This hopper is disposed in superimposed relation to the upper side of the drum from a point slightly to the left of the vertical center line of the drum to a point at the right substantially above the horizontal center line. As indicated in Fig. 2, the left hand end of the opening of the hopper is slightly to the left of the upper vertically disposed powder receiving pocket, while the right hand end of the opening is disposed between the horizontally disposed powder receiving pocket and the inclined pocket above it.

The base 65 of the hopper is circumferentially shaped in concentric relation to the periphery of the drum and engages it in bearing relation, so that the drum constitutes a bottom closure for the opening of the hopper. The rearward wall 66 of the hopper extends upwardly and outwardly in inclined relation from the surface of the drum and with the surface of the drum constitutes a substantially V-shaped area within the hopper wherein the down pressure of the powder within the hopper is most effectually applied to insure filling of the powder receiving pockets of the drum as they are rotated into the opening of the hopper. As most of the weight of the powder in the hopper tends to bear with a wedging action upon that part of the powder in the V-shaped area, and as the inclination of the wall 66 is approximately in line with the axes of the radial powder receiving pockets as they move into the hopper opening the powder will be funneled into the pockets with substantial force and without appreciable restriction. As the pocket entering the hopper opening is of greater area due to the retraction of the plunger 54 at this point, it receives a sufficient charge of powder so that any voids or loose areas are eliminated by the compacting action which takes place when the plunger is projected as it reaches the upper vertical position.

45 The left hand wall 67 of the hopper is vertically disposed and at its lower end is provided with an opening 68 adjacent the periphery of the rotary drum. A vertically disposed resilient guard member 69, preferably formed of relatively soft rubber is engaged against the wall 67, and is provided at its lower end with an arcuate surface 70 conforming to and resiliently engaging the periphery of the drum, its lower end portion being permitted to flex in the opening 68 thereby constituting a resilient seal between the opening of the hopper and the periphery of the drum to clean powder from the surface of the drum and level off the charges of powder contained in the pockets 48.

60 At the left hand side of the rotary drum there is provided a powder retaining member 71 for co-operation with the periphery of the conveyor drum to retain the powder in the pockets during transition from the hopper to the ejecting point, the base 72 of this member being secured to the base plate 10 by means of bolts 73. The retaining member includes a circumferential wall portion 74 concentric to the drum, having a circumferential rib 75 which contacts the surface of the drum as a bearing surface and is slightly wider than the powder containing pockets, so that it constitutes a seal for them. The retaining member 71 is provided with a horizontally disposed platform formation 76 upon which is mounted an automatic stop mechanism for detecting the correct

amount of the powder charge in the pocket in the left hand horizontal position, as will herein-after more fully appear. At the lower end of the rib 75 there is secured a thin metal extension insert 77 secured in a recess pocket 78 in the end of the rib and projecting to a point slightly beyond the lower vertically disposed pocket position and having an ejecting passage 79 therein which registers with the pocket in this position.

Upon the hub portion 43 of the drum 42 there is engaged for oscillatory movement the hub 80 of the drum feeding ratchet lever 81 provided at its lower end with a shouldered stud bolt 82 engaged in a hole 83 therein, and provided upon its forwardly disposed enlarged-diameter headed portion with a pivotally mounted ratchet pawl 84, adapted to ride upon the periphery of the drum and to engage the ratchet notches 50 for imparting intermittent rotary movement to the drum, there being a helical compression spring 85 connected between a pin 86 upon the side of the ratchet pawl and a pin 87 upon the side of the lever, and which draws the ratchet pawl into yielding engagement with the periphery of the drum.

Upon the rearwardly projecting reduced diameter portion of the stud bolt 82 there is rotatably engaged the connecting block member 88 of a connecting rod 89, this member having a cylindrical transverse bore 90 engaged by the stud bolt and being retained upon the stud bolt by means of a nut 91 screwed upon the threaded reduced diameter end portion 92 of the stud bolt. The connecting rod 89 is screwed into a longitudinal threaded passage 93 of the connecting block member and is fixed against displacement by means of a lock nut 94. The other end of the connecting rod 89 is screwed into a threaded passage 95 of a connecting block member 96 and is fixed by means of a lock nut 97, this block member being provided with a transverse cylindrical passage 96a engaged by the eccentric driving pin 98 of a combination eccentric driving and cam plate 99, the hub 100 of which is secured by a pin 101 to the forward end of the cam shaft 25. The connecting block member 96 is secured upon the eccentric pin 98 against outward displacement by means of a cotter pin 102.

With each rotation of the eccentric plate 99 the ratchet lever 81 is oscillated to retract the pawl 84 from the projected position shown in Fig. 2 to its position to engage the next ratchet groove 50 to the left and thereupon through movement to the right the drum 42 is rotated to bring the next pocket to the vertical ejection position.

During the rotary movement of the drum it is free to rotate, but during the retracting movement of the ratchet lever the drum is locked against movement. For this purpose there is provided a reciprocating locking pin 103 slidably supported in a horizontally bored bearing portion 104 formed upon the rearward side of the standard 58 adjacent its top portion 61. The projecting nose of the pin is rounded and adapted in its projected position to engage one of the locking holes 49 of the drum 42 as shown clearly in Figs. 1 and 2, and in the retracted position to become disengaged therefrom to permit the drum to be rotated. The outer end of the pin is provided with a flattened upper surface 105 and a vertically disposed passage 106, and has connected to it, by means of a pivot pin 107 engaged in the passage 106, the forward end of the arm 108 of the

actuating lever for the locking pin. The hub 109 of this lever is supported for pivotal movement upon a vertically disposed bearing post 110 secured in the upper horizontal platform portion of the bracket 40 and is retained against vertical displacement by means of a cotter pin 111 engaged through the upper end of the post.

The rearwardly extending arm 112 of the locking pin actuating lever is engaged at its right hand edge and near its outer end by the upwardly extending arm 113 of a bell crank cam lever, the hub 114 of which is rotatably mounted upon a horizontally disposed shouldered bearing post 115 secured by a force fit in the vertically disposed portion of the bracket 40, and is retained upon the post 115 against lateral displacement by means of a cotter pin 116 engaged through the end of the post. The laterally extending arm 117 of this bell crank cam lever is provided at its end with a roller 118 mounted upon a shouldered headed bearing pin 119 secured by a force fit in the end of the arm and this roller rides upon the periphery of a cam 120, the hub 121 of which is secured upon the cam shaft 25 by means of a pin 122.

A helical compression spring 123 is tied between a pin 124 provided upon the arm 108 of the locking pin actuating lever and a pin 125 mounted in the side of the standard 58, and exerts force upon this lever to project the locking pin 103 and to bring the cam lever into engagement with the periphery of the cam 120, the low surface of the cam allowing the cam lever and actuating lever to rotate under the force of the spring to project the locking pin, and these levers being rotated in the opposite directions as the cam lever rides upon the high surface of the cam to retract the locking pin. Obviously this high surface of the cam is so related to the eccentric driving plate 99 that the locking pin is retracted to free the drum during the portion of rotation of the eccentric plate which actuates the drum feeding ratchet lever in feeding direction.

As the drum 42 is rotated to bring the charges of powder from the hopper to the ejecting point the charges of powder are subjected at the horizontal position midway between the vertical charging point and the vertical ejecting point to the action of an automatic detecting and stop mechanism, this action being designed to detect whether or not there is a correct amount of powder charge in the pocket, and in the event of a deficiency in the amount to stop operation of the machine to enable the operator to divert the deficient charge. The mechanism for accomplishing this action is mounted upon the platform portion 76 of the retaining member 71, and consists of a U-shape block 126 secured by bolts 127 to the platform 76 and provided in the forward faces of the two upright portions with horizontally aligned right angular pockets 128 in which there is slidably engaged a slide rod 129 of rectangular cross-section provided at its inner end with a cylindrical plunger portion 130 in axial alignment with the horizontal pocket 48 of the drum, and having its end surface 130a conforming to and flush with the surface of the rib 75. The slide is retained in the pockets 128 by means of closure plates 131 secured upon the block by screws 132.

A cross bar 133 is secured by bolts 133a upon the upper side of the block 126 adjacent its rearward edge and provides a bearing for the vertically disposed rock shaft 134, the lower end of which projects downwardly into the opening of

the block 126 and has secured thereon a lever arm 135 which projects over the slide rod 129 and engages a vertically disposed pin 136 secured in the slide rod, this pin being normally pressed against the lever by means of a compression helical spring 137 tied between a pin 138 secured upon the forward side of the slide rod near its outer end and a pin 139 secured to the inner surface of the member 71, this spring normally exerting a projecting pressure upon the slide 129 and its plunger portion 130. Upon the upper projecting end of the rock shaft 134 there is secured a lever arm 145 which projects rearwardly in the opposite direction from the arm 135 and which is pivotally connected by means of a pin 141 in the forked end of a connecting block member 142 provided upon one end of a pull rod 143, this pull rod being screwed into a threaded passage 144 in the connecting block member and being secured against displacement by a lock nut 145.

The other end of the pull rod 143 is secured to a similar connecting block member 146 having a threaded passage 147 into which the threaded end of the rod is screwed and secured by a lock nut 148. This connecting block member is pivotally secured to the upwardly extending arm 149 of a cam lever by means of a pin 150, the hub 151 of this cam lever being rotatably mounted upon a horizontal shaft 152, rotatably supported at its forward portion in the cylindrical bearing passage 153 of a bearing formation 154 provided upon the standard 58, and at its rearward end in a bearing hole 155 provided in the vertical portion of the bracket 40. A positioning collar 156 is secured to the shaft 152 by a pin 157 adjacent the inner end of the bearing formation 154 and a positioning collar 158 is secured by a pin 159 of the shaft adjacent the forward end of the hub 151. At the rearward end of the hub 151 there is provided the downwardly extending arm 160 of the cam lever and upon the lower end of this arm there is provided a roller 161 mounted upon a shouldered and headed bearing stud 162 secured by a force fit in the end of the arm 160, this roller riding upon the cam surface 163 of the combination eccentric and cam plate 99, and being pressed into engagement with the cam surface through the action of a spring 140^a tied between a pin 140^b secured to the lever arm 145 and a pin 140^c secured to the block 126.

Upon the outer upright of the block 126 there is mounted a switch unit 36^a connected by conductor wires 36^b in the circuit of the motor 36, this switch unit being normally closed and adapted to be opened through depression of a plunger pin 36^c to a predetermined point. An upright post 129^a is secured to the slide 129 in position to engage the plunger 36^c and actuate the switch upon a predetermined projection movement of the slide to stop the motor. A suitable switch of this character is the "Micro switch" manufactured by Micro Switch Corporation, of Freeport, Illinois.

During engagement of the collar with the high portion of the cam surface 163 the slide 129 is retracted in its normal position as shown in Fig. 2, where it is retained under the pull of the spring 137, by abutment of the pin 136 with the lever arm 135. As it rides upon the low portion of the cam surface the lever arm 135 is rotated inwardly under the pull of the spring 140^a, so that the slide 129 and plunger 130 are free to move inwardly into the pocket under the pull of the spring 137.

In the event that the pocket is completely filled with a powder charge of predetermined density, the projecting movement of the plunger 130 will be arrested through pressure contact with the powder charge, at a point short of the switch actuating point, so that the normal operation of the machine will continue. Should there be a deficiency in the charge the projection of the plunger will be sufficient to actuate the switch and stop the operation of the machine. The operator will thereupon restart the machine by retracting the slide 129, or resetting the switch, and divert the deficient charge when it reaches the ejection point.

At the powder charge ejection point the lower vertically disposed plunger is automatically projected to drive the powder charge out of the pocket into the cartridge shell, which is positioned beneath the drum in line with the ejection point, either manually or by automatic means to successively bring the shells into place in timed relation with the action of the charger. Within the vertical slot 57 of the cam plate 51 there is slidably engaged a block member 164 of rectangular cross-section provided with guide flanges 165-165 at one side which are slidably engaged over the edges of one side of the slot to retain the slide block against lateral displacement. A forwardly projecting pin 166 is secured in the block and this is engaged in the slotted end 167 of a lever 168 having its hub 169 secured upon the forwardly projecting end of the shaft 152 by a pin 170. The lever 168 is bent at its intermediate portion so that the hub end clears the forward edge of the rim portion 45 of the drum 42 and the slotted end is offset inwardly into close relation to the slide block 164. Upon the shaft 152, between the bracket 40 and the cam lever hub 151, there is secured by a pin 171 the hub portion 172 of a cam lever 173, having a roller 174 mounted upon its end by means of a shouldered and headed stud pin 175 secured in the end of the lever by force fit, this roller riding upon the periphery of a cam 176 having its hub portion 177 secured upon the cam shaft 25 between the hub 100 of the cam 99 and the forward side of the bracket 21 by means of a pin 178. The roller is pressed into engagement with the periphery of the cam by means of a helical compression spring 179 tied between a pin 180 secured to the lever 173 and a pin 181 secured upon the forward side of the bracket 40, this spring being substantially greater in strength than the springs 56 of the powder charge ejecting plungers 54, so that as the roller rides upon the low surface of the cam it causes the lever 168 to swing downwardly against the pressure of the spring 56 and depress the slide 164 to project the powder charge ejecting plunger 54, as shown clearly in Fig. 2. As the roller rides upon the high portion of the cam the lever 168 is swung upwardly causing the slide block 164 to be retracted into the slot 57, so that its lower end is substantially flush with the periphery of the cam 51 and is clear of the successive plunger head 55, as it is moved into the vertical ejection position.

The operation is as follows:

As the conveyer drum 42 is intermittently rotated through the action of the ratchet lever 81 the radial powder charge receiving pockets 48 are successively rotated through the following sequence, after leaving the lower vertical ejecting position as shown in Fig. 2. The head 55 of the plunger 54 first rides from the high surface 78 of the cam 51 onto the low surface, so that the

plunger is retracted before the pocket enters the opening of the hopper, thus increasing the capacity of the pocket. In moving from the right hand horizontal position to the first position in the hopper, the pocket passes into the hopper opening in relation to the lower substantially V-shaped area thereof where the substantial weight of the powder in the hopper is concentrated, and due to inclination of the wall 66 and the substantially aligned relation of the pocket therewith a positive feeding of the powder into the pocket results. In moving to the next position in the hopper, namely the upper vertical position, the plunger again moves onto the high surface of the cam and is projected slightly, thus compacting the powder in the pocket upwardly against the weight of the powder in the hopper, thereby eliminating any voids or loose areas therein. In moving to the next position the surface of the drum is wiped by the lower end of the rubber member 69 leveling off the powder in the pocket. Thereupon the pocket moves beneath the rib 75 of the retaining member 71, which retains the powder in the pocket during movement to the next position where the accuracy of the amount of the powder charge in the pocket is tested through the detecting action of the plunger end 130 of the slide 129, which as above pointed out causes automatic stoppage of the machine in the event of a deficiency in the charge. The pocket is thereupon moved through two steps to the lower vertical ejection position at which point the plunger comes into line with the slide 164, which is thereupon depressed through the action of the lever 168, ejecting the charge from the pocket into the cartridge shell, which is placed in line beneath the ejecting point.

The form of the invention illustrated in the drawing and described therein is typical and illustrative only, and it is evident that the invention is capable of embodiments in other forms, all falling within the scope of the appended claims which are to be broadly construed.

What is claimed is:

1. In an automatic powder charger for cartridge shells, a rotatable conveyer member having a series of powder receiving pockets, drive means arranged to rotate said conveyer member intermittently through equal increments of movement corresponding to the spacing of said pockets, a powder containing hopper disposed above said conveyer member having an opening in communication with said pockets as they are moved into relation to said hopper, reciprocating plunger means constituting bases for said pockets and adapted through projecting movement to eject said powder from said pockets, a second reciprocating plunger means arranged radially of said rotatable conveyer to engage in said pockets at a point between said hopper and said ejection point to detect the amount of powder therein, and stop means for stopping the conveyer member arranged to be actuated by said second plunger means.

2. In an automatic powder charger for cartridge shells, a rotatable cylindrical conveyer member having a series of radially disposed passages extending to its periphery, plunger members disposed in said passages constituting movable bases for powder receiving pockets formed by said passages in the periphery of said conveyer member, a powder containing hopper disposed above said conveyer member having a longitudinal discharge opening in continuous communication with said pockets as they are moved into

relation to said hopper, and actuating means for said plungers adapted as said conveyer member is rotated to move said plungers from a normal retracted position as they enter said hopper opening to a more retracted position whereby an excess of powder flows into said pockets and then to an advanced position to diminish the volume of said pockets whereby at least some of the powder received in the pockets is moved relatively thereto through reduction in the volume of said pockets.

3. In an automatic powder charger for cartridge shells, a rotatable cylindrical conveyer member having a series of radially disposed passages extending to its periphery, plunger members disposed in said passages constituting movable bases for powder receiving pockets formed by said passages in the periphery of said conveyer member, a powder containing hopper disposed above said conveyer member having a longitudinal discharge opening in continuous communication with said pockets as they are moved into relation to said hopper, spring means exerting retracting pressure on said plungers, stationary cam means engaged by said plungers through the action of said spring means adapted as said conveyer member is rotated to impart movement to said plungers to successively increase and diminish the volume of said pockets whereby at one point at least some of the powder received in the pockets is moved relatively thereto through reduction in the volume of said pockets, and vertically reciprocating actuating means mounted on said cam means arranged to impart projecting movement to each plunger successively at one point in the rotation of said conveyer member to eject powder from the pockets.

4. In an automatic powder charger for cartridge shells, a rotatable cylindrical conveyer member having a series of radially disposed passages extending to its periphery, plunger members disposed in said passages constituting movable bases for powder receiving pockets formed by said passages in the periphery of said conveyer member, a powder containing hopper disposed above said conveyer member having an opening in communication with said pockets as they are moved into relation to said hopper, reciprocating actuating means arranged to impart projecting movement to each plunger at one point in the rotation of said conveyer member to eject powder from said pockets, means for actuating said reciprocating means comprising a lever arm pivotally secured thereto, and a cam for positively actuating said lever arm.

5. In an automatic powder charger for cartridge shells, a rotatable cylindrical conveyer member having a series of radially disposed passages extending to its periphery, drive means arranged to rotate said conveyer member intermittently through equal increments of movement corresponding to the spacing of said pockets, plunger members disposed in said passages constituting movable bases for powder receiving pockets formed by said passages in the periphery of said conveyer member, a stationary cam engaged by said plunger members for displacing said members in said pockets, said cam having a slot, a powder containing hopper disposed above said conveyer member having an opening in communication with said pockets as they are moved into relation to said hopper, reciprocating actuating means supported in said cam slot to impart projecting movement to each plunger at one point in the rotation of said con-

veyer member to eject powder therefrom, means for reciprocating said actuating means in said slot, reciprocating plunger means arranged to engage said pockets at a point between said hopper and said ejection point to detect the amount of powder therein, and stop means arranged to be actuated by said plunger means.

6. In an automatic powder charger for cartridge shells, a rotatable cylindrical conveyer member having a series of radially disposed passages extending to its periphery, drive means arranged to rotate said conveyer member intermittently through equal increments of movement corresponding to the spacing of said pockets, plunger members disposed in said passages constituting movable bases for powder receiving pockets formed by said passages in the periphery of said conveyer member, a powder containing hopper disposed above said conveyer member having an opening in communication with said

5 pockets as they are moved into relation to said hopper, actuating means for said plungers adapted as said conveyer member is rotated to impart movement to said plungers to successively increase and diminish the volume of said pockets while said pockets are opposite the opening in said hopper and subjected to the pressure of powder therein whereby at one point at least some of the powder received in the pockets is moved relatively thereto through reduction in the volume of said pockets, reciprocating actuating means arranged to impart projecting movement to said plungers at one point in the rotation of said conveyer member to eject powder from said pockets, reciprocating plunger means arranged to engage said pockets at a point between said hopper and said ejection point to detect the amount of powder therein, and stop means arranged to be actuated by said plunger means.
